US00D891570S

(12) **United States Design Patent** (10) Patent No.: **US D891,570 S**
(45) Date of Patent: **** Jul. 28, 2020**

(54) **AMMUNITION CARTRIDGE NOSE**

865,979 A 9/1907 Bailey
869,046 A 10/1907 Bailey
905,358 A 12/1908 Peters
957,171 A 5/1910 Loeb
963,911 A 7/1910 Loeb
1,060,817 A 5/1913 Clyne
1,060,818 A 5/1913 Clyne

(71) Applicant: **True Velocity IP Holdings, LLC**,
Garland, TX (US)

(Continued)

(72) Inventors: **Lonnie Burrow**, Carrollton, TX (US);
Christopher William Overton, Wylie,
TX (US); **Nimmy Mammoottil**,
Richardson, TX (US); **Florian Herzog**,
Dallas, TX (US)

FOREIGN PATENT DOCUMENTS

(73) Assignee: **TRUE VELOCITY IP HOLDINGS, LLC**,
Garland, TX (US)

CA 2813634 A1 4/2012
CN 102901403 B 6/2014
(Continued)

(**) Term: **15 Years**

OTHER PUBLICATIONS

(21) Appl. No.: **29/683,249**

AccurateShooter.com Daily Bulletin "New PolyCase Ammunition
and Injection-Molded Bullets" Jan. 11, 2015.

(22) Filed: **Mar. 12, 2019**

Primary Examiner — Michael A. Pratt

(51) LOC (12) Cl. **22-16**

(74) Attorney, Agent, or Firm — Chainey P. Singleton

(52) U.S. Cl.

USPC **D22/116**

(58) **Field of Classification Search**

USPC **D22/115-116**

See application file for complete search history.

(57) **CLAIM**

The ornamental design for an ammunition cartridge nose, as
shown and described.

(56) **References Cited**

DESCRIPTION

U.S. PATENT DOCUMENTS

99,528 A	2/1870	Boyd
113,634 A	4/1871	Crispin
130,679 A	8/1872	Whitmore
159,665 A	2/1875	Gauthey
169,807 A	11/1875	Hart
207,248 A	8/1878	Bush et al.
462,611 A	11/1891	Comte de Sparre
475,008 A	5/1892	Bush
498,856 A	6/1893	Overbaugh
498,857 A	6/1893	Overbaugh
640,856 A	1/1900	Bailey
662,137 A	11/1900	Tellerson
676,000 A	6/1901	Henneberg
743,242 A	11/1903	Bush

FIG. 1 is an isometric view of an ammunition cartridge nose
showing my new design of the nose portion of an ammu-
nition cartridge.

FIG. 2 is a top view of my new design of the nose portion
of an ammunition cartridge.

FIG. 3 is a cross sectional view along 3-3 of FIG. 2 showing
my new design of the nose portion of an ammunition
cartridge; and,

FIG. 4 is a cross sectional view along 4-4 of FIG. 2 showing
my new design of the nose portion of an ammunition
cartridge.
